EDWIN S. LAMMERS, JR., OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRICAL SYSTEM.

1,406,565.

Specification of Letters Patent. Patented Feb. 14, 1922.

Application filed November 16, 1917. Serial No. 202,337.

To all whom it may concern:

Be it known that I, EDWIN S. LAMMERS, Jr., a citizen of the United States, and a resident of Wilkinsburg, in the county of Allegheny and State of Pennsylvania, have invented a new and useful Improvement in Electrical Systems, of which the following is a specification.

My invention relates to systems of control for electric motors and particularly to systems of control for electric motors that serve for operating rolling mills.

One object of my invention is to provide a control system of the above-indicated character that shall control the acceleration of the motor or motors associated with the rolls of a mill in a manner to insure the acceleration of the mill to full speed in a given length of time.

In rolling-mill work, it is desirable to have the motors, which are connected to the various sets of rolls, accelerate in the shortest possible time without any unnecessary delay. Moreover, it is essential for good operation that the various sets of rolls be accelerated in a reliable and steady manner, whether the mill is running light or is operating on a piece of material.

In the usual control systems now in service, the motors, which are connected to the various sets of rolls, are accelerated in accordance with the current flowing through the motors. Thus, if the rolls are running light and unloaded, the mill will be accelerated in a very short length of time but, if the rolls of the mill are in any way loaded, the time for accelerating the mill will be materially increased by reason of the increased amount of current flowing through the motors. Such a method of acceleration is undesirable in rolling-mill work, by reason of the time lost when the rolls are in any way loaded.

In a control system constructed in accordance with my invention, means that is governed in accordance with the current flowing through the motors is provided for effecting acceleration of the motors in the shortest possible time, under normal operating conditions, and a second auxiliary means is provided for effecting acceleration of the motors in a predetermined length of time, in case the first-mentioned means fails to accelerate the motors to full speed.

In the accompanying drawing, Fig. 1 is a

diagrammatic view of a control system constructed in accordance with my invention; Fig. 2 is a diagrammatic view of the main circuits of the operating motor; Fig. 3 is a diagram illustrating the sequence of operation of the various switches; and Fig. 4 is a plan view of one of the accelerating switches illustrated in Fig. 1 of the drawing.

Referring to the accompanying drawing, a motor 1, embodying an armature 2, a series field winding 3, a compensating field winding 4 and a shunt field winding 5, is connected in series with the resistors 6, 7 and 8 across a supply circuit 10 by means of a line switch 11 and line switches 12 and 13. The line switches 12 and 13 respectively embody energizing coils 14 and 15 and contact members 16 and 17. A plurality of resistor switches 18, 19 and 20, respectively embodying energizing coils 21, 22 and 23 and contact members 24, 25 and 26 are adapted to short-circuit the resistors 6, 7 and 8 in order to effect acceleration of the motor 1.

A plurality of accelerating switches 27, 28 and 29 are associated with the switches 13, 18 and 19 and are adapted to be operated thereby. The accelerating switch 27 embodies a core member 30 having a switch member 31 connected thereto which bridges contact members 32 when in a released position. The core member 30 is normally held in a raised position by means of a coil spring 33 that is disposed between a stationary support 34 and a rod 35 which is rigidly mounted upon the core member 30. A bar 36, which is pivotally mounted intermediate its ends, is pivotally connected, near one end thereof, to the core member of the line switch 13 and is provided with suitable bifurcated arms at the other end thereof, so disposed as to compress the spring 33 and relieve the core member 30 from the action thereof whenever the line switch 13 is operated. Thus, the accelerating switch 27 is normally held in an open position by means of a coil spring 33 and, when the line switch 13 is operated, is under the control of a coil 37. The accelerating switches 28 and 29 respectively embody energizing coils 38 and 39 and contact members 40 and 41 and are controlled by the resistor switches 18 and 19, in a manner similar to the control of the accelerating switch 27 by the line switch 13.

A relay 40a, embodying an energizing coil 41a, a switch member 42 and an interlock 110

switch 43, is provided for governing various auxiliary control circuits. An overload relay 44, embodying a coil 45 and switch member 46, is provided for preventing an abnormal current flow through the motor 1. A start button 47 and a stop button 48 are respectively provided for initiating and stopping the operation of the system.

A drum controller 50 embodies contact segments 51 and 52 which are adapted to engage contact fingers 53 to 61, inclusive, when the controller is moved through its various operative positions by means of a pilot motor 62. The pilot motor 62 embodies an armature 63 and a shunt field winding 64. The drum controller 50, which is operated by the pilot motor 62, serves for effecting acceleration of the motor 1, irrespective of the operation of the accelerating switches 27, 28 and 29.

Assuming the elements of the system to be in the positions illustrated in Fig. 1, the motor 1, which may be connected to a set of rolls of a rolling mill or to any other suitable load, is energized and accelerated to full speed by operating the start button 47. When the start button 47 is closed, a circuit is completed from the negative supply conductor through the switch 11, interlock switch 43, which is associated with the relay 40a, start button 47, pilot motor 62 and switch 11 to the positive supply conductor. The pilot motor 62 is thus energized and the drum controller 50 advanced from the off position to position *a*.

In position *a* of the drum controller 50, a circuit is completed for the pilot motor 62 from the negative supply conductor through the switch 11, contact terminals 59 and 60, which are bridged by the contact segment 52, pilot motor 62 and the switch 11 to the positive supply conductor. The circuit, above traced through the pilot motor 62, serves for maintaining the circuit of the pilot motor until the final operating position *f* of the drum controller is reached, at which point the contact segment 52 breaks contact with the contact terminals 59 and 60. In position *a* of the drum controller, circuits are also completed for the energizing coils 41a, 15 and 14 of the relay 40a and the line switches 13 and 12. The circuit for coils 14 and 15 is from the negative supply conductor, through the switch 11, contact fingers 59 and 61—which are bridged by the contact segment 52—in parallel through the coils 15 and 14 and the switch 11, to the positive supply conductor. The circuit for the coil 41a is from the negative supply conductor, through contact terminals 59 and 61—which are bridged by the contact segment 52—coil 41a, contact member 46, stop button 48 and switch 11, to the positive supply conductor.

The relay 40a is energized to operate the interlock 43 and break the circuit previously

traced through the start button 47 and to complete a holding circuit for the coils 41a, 15 and 14 through the switch member 42. The holding circuit for the coil 41a is from the positive supply conductor, through the switch 11, stop button 48, contact member 46 of the switch 44, coil 41a, switch member 42 and the switch 11, to the negative supply conductor. The holding circuit for coils 14 and 15 is completed from the negative supply conductor, through switch 11, switch member 42, coils 14 and 15 in parallel, and the switch 11, to the positive supply conductor.

The line switches 14 and 15 are operated in order to complete a circuit through the motor 1 that is from the positive supply conductor through the switch 11, contact member 17 of the line switch 13, coil 37 of the accelerating switch 27, resistors 6, 7 and 8, armature 2, field windings 3 and 4 of the motor 1, contact member 16 of the line switch 12, coil 45 of the switch 44 and the line switch 11, to the negative supply conductor.

When the line switch 13 is operated, the accelerating switch 27 is relieved from the influence of the coil spring 33 and is controlled solely by the motor current that is flowing through the coil 37. Thus, when the motor current is reduced to a predetermined point, the contact member 31 is lowered to bridge the contact members 32 and complete a circuit through the energizing coil 21 of the resistor switch 18. The circuit through the coil 21 extends from the negative supply conductor, through the switch 11, contact fingers 59 and 61—which are bridged by contact segment 52—contact fingers 32—which are bridged by contact member 31 of the switch 27—coil 21 and the switch 11, to the positive supply conductor. Thus, the resistor switch 18 is operated to short-circuit the resistor 8 by means of the contact member 24. The accelerating switch 28 is now controlled solely by the motor current passing through the coil 38 and, when the motor current is reduced to a predetermined point, the contact member 40 is lowered to complete a circuit through the energizing coil 22 of the resistor switch 19. The circuit of the coil 22 is from the negative supply conductor, through the switch 11, contact fingers 59 and 61—which are bridged by the contact segment 52—contact member 40, coil 22 and the switch 11, to the positive supply conductor. Thus, the resistor switch 25 is operated to short-circuit the resistor section 7.

When the resistor switch 19 is operated, the accelerating switch 29 is controlled by the energizing coil 39 and, when the motor current which is passing through the coil 39 is reduced to a predetermined point, the contact member 41 is lowered to complete a

circuit through the coil 23 of the resistor switch 20. The circuit through the coil 23 is from the negative supply conductor through the switch 11, contact fingers 59 and 61—which are bridged by contact segment 52—contact member 41, coil 23 and switch 11 to the positive supply conductor. The resistor switch 20, by means of the contact member 26, short-circuits the last resistor 6 and permits the motor 1 to operate at full speed.

In case it is desired to stop the motor at any time, the stop button 48 is operated to break the circuit previously traced through the coil 41a of the relay 40a and thus open the relay 40a for releasing the line switches 12 and 13 to open the motor circuit. In case the motor 1 draws an abnormal amount of current, the overload relay 44 is operated to break the energizing circuit of the relay 40a and thus release the line switches to break the motor circuit.

In case the motor 1 is operating under a load of such proportions as to prevent the coils 37, 38 and 39 of the accelerating switches 27, 28 and 29 from releasing the respective contact members 31, 40 and 41, the motor 1 is not accelerated to full speed unless auxiliary means is provided. If the accelerating switch 27 is not operated to complete the circuit through the energizing coil 21 of the resistor switch 18, when the drum 50 is moved to position *b* by the pilot motor 62, a circuit is completed by the drum controller 50 through the coil 21. The circuit through the drum 50 is from the negative supply conductor, through the switch 11, switch member 42, contact fingers 53 and 58—which are bridged by the contact segment 51—coil 21 and switch 11, to the positive supply conductor. The resistor switch 18 is thus operated to short-circuit the resistor 8 and, in case the accelerating switch 28 fails to operate before the drum controller 50 is advanced to position *d*, the circuit for the coil 22 of the resistor switch 19 is completed through the drum controller 50. The circuit of the coil 22, that is completed through the drum controller 50, is from the negative supply conductor through the switch 11, switch member 42, contact fingers 53 and 56—which are bridged by the contact segment 51—coil 22 and switch 11 to the negative supply conductor. Thus, the resistor switch 19 is operated to short-circuit the resistor 7, and, in case the accelerating switch fails to operate before the drum controller 50 is advanced to position *f*, a circuit through the coil 23 of the resistor switch 20 is completed through the drum controller 50. The circuit for the coil 23, that is completed through the drum controller 50, is from the negative supply conductor, through switch 11, switch member 42, contact fingers 53 and 54—which are

bridged by the contact segment 51—coil 23 and the switch 11, to the positive supply conductor.

Thus, it will be noted that means, comprising the accelerating switches 27, 28 and 29, is provided for accelerating the motor 1 in accordance with the current flowing therethrough, and, in case the above-mentioned means fails to operate, because of an abnormal load upon the motor or for any other reason, the motor will be accelerated in a predetermined time, independent of the accelerating switches 27, 28 and 29, by means of the drum controller 50 which is operated by the pilot motor 62.

Modifications in the system and arrangement and location of parts may be made within the spirit and scope of my invention, and such modifications are intended to be covered by the appended claims.

I claim as my invention:

1. In a system of control, the combination with a motor, and resistors initially connected in series with said motor, of means comprising a plurality of resistor switches having accelerating switches associated therewith for short-circuiting said resistors in accordance with the current flowing through the motor, and means for automatically effecting operation of said resistor switches independently of said accelerating switches.

2. In a system of control, the combination with a motor, a plurality of resistors initially connected in series with the motor, and a plurality of resistor switches for excluding said resistors from the motor circuit, of means, comprising accelerating switches, for operating the resistor switches in accordance with the current flowing through the motor, and means, comprising a motor-operated controller, for successively operating said resistor switches at the end of a predetermined time interval.

3. In a system of control, the combination with a motor, a plurality of resistors initially connected in series with the motor, and a plurality of electrically operated resistor switches for excluding the resistors from circuit, of accelerating switches, controlled by certain of said resistor switches, for operating predetermined resistor switches in accordance with the current flowing through the motor, and means, comprising a motor-operated controller, for operating said resistor switches at the end of a predetermined time interval, independently of the current flowing through the motor.

4. In a system of control, the combination with a motor, a plurality of resistors initially connected in series with the motor, and a plurality of resistor switches for excluding the resistors from the motor circuit, of means for governing the operation of said resistor switches in accordance with the current flowing through the motor,

means, comprising a motor-operated controller, for operating said resistor switches in case the first mentioned means fails to operate within a predetermined time interval, manual means for initiating the operation of said controller, and automatic means for stopping the operation thereof.

5. In a system of control, the combination with a motor, a plurality of resistors initially in series with said motor, and a plurality of resistor switches for excluding the resistors from the motor circuit, of means, comprising a plurality of accelerating

switches, for effecting operation of the resistor switches in accordance with the current flowing through the motor, means comprising a motor-operated controller, for operating the resistor switches in case the first named means fails to complete its operation within a predetermined time interval, and a single switch for initiating the operation of both of said means. 15 20

In testimony whereof, I have hereunto subscribed my name this 26th day of Oct., 1917.

EDWIN S. LAMMERS, JR.
